UNITED STATES PATENT OFFICE.

EINAR N. RAULAND, OF RIVER FOREST, ILLINOIS.

DESIGN FOR A RADIO RECEIVER CABINET.

Application filed August 25, 1926. Serial No. 18,859. Term of patent 3½ years.

To all whom it may concern:

Be it known that I, EINAR N. RAULAND, a citizen of the United States, residing at River Forest, in the county of Cook and State of Illinois, have invented a new, original, and ornamental Design for Radio Receiver Cabinet, of which the following is the specification, reference being had to the accompanying drawing, forming part thereof.

The figure is a perspective view of the radio receiver cabinet showing my new design.

I claim:

The ornamental design for a radio receiver cabinet as shown.

EINAR N. RAULAND.
